UNITED STATES PATENT OFFICE

NATHAN M. LOWER AND PAUL A. KETCHPEL, OF PITTSBURGH, PENNSYLVANIA, AS
SIGNORS, BY MESNE ASSIGNMENTS, TO THE STANDARD STOKER COMPANY INC.,
OF NEW YORK, N. Y., A CORPORATION OF DELAWARE

STOKER MECHANISM

Application filed February 26, 1926. Serial No. 90,717.

This invention relates to stokers, and more particularly to mechanical stokers and means for controlling the operation of the same.

One of the objects of the invention is the provision of new and improved means for controlling the relative amounts of fuel delivered to different portions of the firebox.

Another object of the invention is the provision of a reciprocating elevator with new and improved mechanism for selectively delivering fuel to said elevator at each cycle or each alternate cycle of movement of the elevator as may be desired.

A further object of the invention is the provision of new and improved stoker mechanism that is simple in construction, efficient in operation, cheap in manufacture, easily assembled, and that is not likely to become broken or get out of order.

Other and further objects and advantages of the invention will appear from the following description taken in connection with the accompanying drawings, in which

Fig. 1 is a side elevation of a portion of the stoker mechanism, with parts in section and parts broken away;

Fig. 2 is a vertical section on line 2—2 of Fig. 1;

Fig. 3 is a plan view of a portion of a stoker showing the backhead of the locomotive in section, with parts broken away;

Fig. 4 is a rear elevation of a portion of the vane operating mechanism;

Fig. 5 is a side elevation on an enlarged scale of the clutch mechanism;

Fig. 6 is a section on line 6—6 of Fig. 5;

Fig. 7 is a side elevation of a portion of the stoker, showing a portion of the backhead of a locomotive in section, with parts broken away;

Fig. 8 is a developed view of the radial flanges of the clutch mechanism; and

Fig. 9 is a vertical section of the gear and journal of one of the fuel delivery vanes.

On the drawings the reference character 10 designates the backhead of a locomotive provided with an opening 11 therein, through which fuel is supplied to the firebox 12 by means of the improved stoker 13, located at the rear of the backhead.

The stoker 13 comprises a casing 14 in which a plunger 15 is adapted to reciprocate, suitable guides being provided for the plunger. The upper end of the casing has a rearward extension 16 forming an enlarged 55 receptacle or chamber 17. A distributor plate 20 of any approved construction is located over the recess or chamber 17 and has an extension 18 extending through the opening 11 in the backhead 10 of the locomotive. 60

Suitable means are provided for operating the plunger 15. As shown, it is operated from the power shaft 19 through a worm 22, gear 23 fast on the shaft 24, gears 25 and 26, the latter being fast on the shaft 28, a crank 65 arm 29 rigidly secured to the shaft 28, and a link 31 connected to said crank arm 29 and to the plunger 15 as at 32. The power shaft 19 is operated in the usual manner by an engine on the side of the stoker remote from the fly wheel 21.

The lengths of the crank arm 29 and link 31 are such that when the plunger 15 is in its lowermost position the upper surface thereof forms a portion of the bottom wall of the chamber 17. When the plunger is in its uppermost position it extends through a suitable opening 33 in the distributor plate 20 with its upper surface flush with the upper surface of the distributor plate. The distributor plate may be provided with walls 34 for forming a receptacle for receiving fuel elevated by the plunger 15. 75

Suitable means, as the swinging vanes 35 and 36 are provided for projecting the fuel from the distributor plate or member into the firebox. As shown, the vanes are mounted on the shafts 37 upon the lower ends of which gears 38 are secured. The gears are adapted to be oscillated by the toothed quadrants 39 on the upper ends of the arms 41. The arms 41 are pivoted as at 42 and their lower ends are provided with studs 43 that are adapted to engage the cam way 44 on the cam member or plate 45 secured to the shaft 24. As the cam member 45 rotates it will cause the arms 41 to oscillate, and through them the vanes 35 and 36 will be caused to oscillate to sweep the fuel brought up by the elevator into the firebox. 80 85 90 95 100

The parts are so arranged that the plunger reciprocates for each oscillation of the vanes. This is accomplished through the gear ratio of the gears 25 and 26, causing the shaft 28 to rotate twice as fast as the shaft 24. Furthermore, the cam way is so arranged that the vanes will be moved forwardly at the time the plunger 15 is flush with the distributor plate. The plunger and vanes operate continuously in timed relation during the operation of the stoker.

Fuel is delivered to the chamber 17 above the plunger through a suitable conveyor comprising the transfer conduit or casing 46 in which is rotatably mounted the screw 47. The conduit 46 is flexibly connected to the elevator casing as by means of a ball and socket joint 48 which will permit angular movement of said conduit relatively to the elevator casing. The fuel transfer screw 47 may be operated in any suitable manner, as by means of the shaft 49 geared to the power shaft 19. Its operation is continuous and uniform during the operation of the stoker, thereby causing a continuous stream of fuel to be delivered to the chamber 17.

In the stoking of locomotive and other power plants, it is often necessary to trim the fire at one side of the box to the exclusion of the other. Suitable means are accordingly provided for selectively trimming the fire at either side of the firebox at the will of the fireman or stoker operator.

In the form of the device selected to illustrate one embodiment of the invention, means are provided for interrupting the flow of fuel to the plunger whereby either one or the other of the vanes will not be provided with fuel, as may be desired. This is accomplished by means of a gate or sliding member 51 which may be caused to reciprocate in timed relation to the operation of the elevator, and at one half of the speed. Since the vanes operate alternately, and continuously at regular intervals, by stopping the flow of fuel to either vane, the other vane will have twice its normal load to distribute, thereby trimming the fire at that side of the firebox. In the present construction, suitable means are provided for operating the gate 51 to obstruct the flow of fuel to either the right or the left vane when it is desired to trim the fire a one side or the other.

The gate 51 is slidably mounted in guide-ways 50 and is operated by the shaft 52 through the crank 53 and link 54. The shaft 52 is operated from the shaft 24 as by means of the chain drive 55. The sprocket wheels 56 and 57 on the shafts 24 and 52 respectively being of the same diameter, the two shafts will rotate at the same speed, and since the shaft 24 rotates at only one-half the speed of the shaft 28, when the shaft 52 operates it will cause the gate 51 to operate at one half the speed of the elevator.

The means for controlling the operation of the gate for selectively preventing fuel from being delivered to the right or the left vane, will now be described. The sprocket wheel 57 is rotatably mounted on the sleeve 58 which in turn is keyed to and slidably mounted on the crank shaft 52. If desired, a bushing 60 may be secured in the sprocket wheel 57 for loosely engaging the sleeve 58. Manually controlled clutch mechanism is employed for clutching the shaft 52 to the sprocket wheel 57 for operating said shaft or for moving the clutch to neutral position. As shown, the outer end of the sleeve 58 is provided with a head 59 having a tooth 61 for engaging a corresponding recess 62 in the outer side of said sprocket wheel 57. The inner end of the sleeve 58 is provided with a grooved disk 63 which is also provided with a tooth 64 for engaging a corresponding recess 65 on the inner side of the sprocket wheel 57. It will be noted that the teeth 61 and 64 are arranged at an angle of 180° from each other, whereby when the tooth 61 engages the recess 62 in the sprocket wheel 57, the gate 51 will be operated to prevent the delivery of fuel to one of the vanes during its forward movement, and when the tooth 64 engages the recess 65 on the opposite side of the sprocket wheel 57 the gate 51 will be elevated to prevent the delivery of fuel to the other vane during its forward swinging movement.

Means are provided for shifting the sleeve 58 for engaging and disengaging the clutch mechanism. The clutch mechanism is operated by means of a shifting bar 66 slidably mounted in suitable bearings 67 and provided at its inner end with a yoke 68 which is adapted to engage in the groove 70 in the disk 63. The shifting bar 66 is operated by a pull rod 69 through a bell crank lever 71 pivotally attached to said bar. The upper end of the pull rod 69 is provided with a slot 72 having seats 73 therein for receiving a bolt 74 for holding the rod in adjusted position. The bolt 74 may be provided with a wing nut 75 for clamping the rod for preventing its accidental disengagement from said bolt.

In order that when the clutch is disengaged the gate 51 may not be left in elevated or partially elevated position, suitable means are provided for preventing operation of the clutch except when the gate is in its retracted position.

As shown, the sprocket gear 57 is provided with a hub 76 on the periphery of which are the radial flanges 77 and 78 (see Figs. 1 and 8). The flange 77 is provided with a cut-out portion or opening 79 and the flange 78 is provided with a cut-out portion or opening 81 located 180° from the opening 79. The shifting bar 66 is provided at its outer end with a radial extension or timer lug 82 which is adapted to pass through the opening 79 or 81 when it is opposite the same. These

openings are so arranged that the timer lug 82 can not be moved through the same except when the gate 51 is in its lower position. When the timer lug is moved so that it engages between the radial flanges 77 and 78, the clutch mechanism is in neutral and the gate 51 is lowered position.

When the timer lug 82 has moved outwardly through the opening 79, the clutch 10 will be in the position shown in Fig. 1, and the gate 51 will operate to prevent delivery of fuel to the left vane during its operation. If the timer lug 82 be moved inwardly through the openings 79 and 81 the tooth 64 15 will become engaged and the gate 51 will be operated to prevent the delivery of fuel to the right vane during its operation.

When it is desired to shift the clutch, the wing nut 75 is released and the bar 69 raised 20 or lowered to adjusted position.

It is thought from the foregoing taken in connection with the accompanying drawings that the construction and operation of our device will be apparent to those skilled in the 25 art, and that various changes in size, shape, proportion and details of construction may be made without departing from the spirit and scope of the appended claims.

We claim as our invention:

30 1. In a stoker, a distributor plate, a plunger for delivering fuel to said plate, means for operating said plunger, a chamber traversed by said plunger, means for delivering a stream of fuel to said chamber, means for interrupting the flow of fuel to said chamber during alternate reciprocation only of said plunger, and means adapted to distribute said fuel over the grates of a fire box.

2. In a stoker, a distributor plate, a plunger 40 for delivering fuel to said plate, swinging vanes for projecting the fuel from said plate, means for delivering a stream of fuel above said plunger while in lowered position, and means operating in timed relation to said 45 vanes for interrupting the flow of said stream.

3. In a stoker, a distributor plate, a pair 50 of swinging vanes for throwing fuel from said plate, an elevator for supplying fuel to said plate, means for causing a stream of fuel to flow above said elevator, and manually controlled means for intercepting the flow of said stream.

4. In a stoker, a reciprocating elevator, a transfer screw for delivering a continuous 55 stream of fuel to the space traversed by said elevator, manually controlled means for interrupting the flow of said stream at each alternate reciprocation of said elevator to the exclusion of the other, and means for distributing 60 said fuel over the grates of a fire box.

5. In a stoker, a casing having an enlarged 65 chamber in its upper portion, a plunger in said casing, means for supplying a stream of fuel to said chamber, manually controlled means for interrupting the flow of said

stream at each alternate cycle only in the operation of said plunger, and means for projecting said fuel forwardly at each upward reciprocation of said plunger.

6. In combination, a firebox, a distributor 70 member associated therewith, an elevator for delivering fuel to said member, a pair of swinging vanes for projecting the fuel from said member into said firebox, a chamber above said elevator, means for delivering a 75 stream of fuel to said chamber, and means for interrupting the stream of fuel in timed relation to the swinging of one of said vanes.

7. In a stoker, a fuel chamber, means for supplying a stream of fuel to said chamber, 80 a gate for interrupting the flow of said stream to said chamber, mechanism including a clutch for operating said gate, and means for preventing the disengagement of said clutch except when said gate is in its inoperative 85 position.

8. In a stoker, a fuel elevator, a fuel conveyor for delivering fuel to said elevator, a movable gate, means including a clutch for operating said gate to prevent the delivery 90 of fuel to said elevator by said conveyor, and means for preventing the operation of said clutch except when said elevator is in a predetermined position in its cycle of operation.

9. In combination, a firebox of a boiler having 95 an opening in its back wall, a fixed distributor plate extending into said opening, a pair of fuel projecting means for projecting fuel from said plate alternately to opposite sides of said firebox, mechanism for supplying fuel to said means, and manually controlled means for intercepting the supply of fuel to either of said projecting means to the exclusion of the other.

10. In a stoker, a fixed distributor plate, a 105 pair of fuel distributing members for projecting fuel from said plate, means for alternately operating said members, means for automatically supplying fuel on said plate for each of said members, and manually controlled 110 means for intercepting the supply of fuel to said plate for either of said members to the exclusion of the other.

11. In combination, a distributor member, an elevator for delivering fuel to said distributor member, means for operating said elevator, a casing traversed by said elevator, means for delivering a flow of fuel to said casing, means for intermittently interrupting the flow of fuel to said casing and means 120 for manually controlling the operation of said last named means.

In testimony whereof we affix our signatures.

NATHAN M. LOWER. 125
PAUL A. KETCHPEL.
